US0D1114067S

(12) **United States Design Patent** (10) **Patent No.:** **US D1,114,067 S**
(45) **Date of Patent:** **** Feb. 17, 2026**

(54) **LABEL**

(71) Applicant: **Eli Lilly and Company**, Indianapolis, IN (US)

(72) Inventors: **Fernando Ludwig Fernandez Marin**, Maplewood, NJ (US); **Frank N. Hockmuller**, Noblesville, IN (US); **Yuchen Liu**, Flushing, NY (US); **Ross Stephen Merkel**, Fishers, IN (US); **Joseph Vito Primiani**, Astoria, NY (US); **J Geoffrey Swope**, Indianapolis, IN (US)

(73) Assignee: **Eli Lilly and Company**, Indianapolis, IN (US)

(**) Term: **15 Years**

(21) Appl. No.: **30/004,329**

(22) Filed: **May 19, 2025**

Related U.S. Application Data

(60) Division of application No. 29/867,501, filed on Oct. 27, 2022, now Pat. No. Des. 1,075,920, which is a continuation of application No. 29/838,534, filed on May 13, 2022, now Pat. No. Des. 1,072,050.

(57) **CLAIM**

The ornamental design for a label, as shown and described.

DESCRIPTION

FIG. 1 is a front, top, right perspective view of a label shown in an environment of use;

FIG. 2 is a rear view thereof;

FIG. 3 is a front view thereof;

FIG. 4 is a left side view thereof;

FIG. 5 is right side view thereof;

FIG. 6 is a top plan view thereof; and,

FIG. 7 is a bottom plan view thereof.

The autoinjector shown in even broken lines depicts environment that does not form part of the claimed design.

1 Claim, 3 Drawing Sheets
